PAPERBOARD TRAY

Bernard J. Miller, Braddock, Pa., assignor to St. Regis Paper Company, New York, N.Y., a corporation of New York

Filed Dec. 10, 1962, Ser. No. 243,418

2 Claims. (Cl. 229—34)

This invention relates to trays which may be formed of sheet material such as paperboard, for example rigid or semi-rigid corrugated double-faced kraft fibreboard.

Trays made in accordance with the invention are particularly adaptable, among other possibilities, for use as collapsible or disposable hospital trays, for example for purposes such as carrying food or drinks or for use by doctors and nurses in carrying instruments or other equipment.

The invention provides a construction which may be cut from a single sheet of corrugated paperboard or other inexpensive sheet material, the tray as initially formed being cut to the desired shape and with certain crease or fold lines and weakened lines formed thereon so that the same may be stored in flat condition, whereby even large numbers of the trays require very little space for storage, yet providing a construction which can be conveniently set up into tray form with self-locking rail formations at the perimeter thereof, without the use of tools or additional materials. The set-up tray will have no exposed rough or cutting edges, yet a very lightweight construction is provided which is easy for infirm patients to handle and which, when the rail formations at the edges thereof are folded into place, will provide a relatively strong and firm structure having adequate weight capacity for its intended purposes, the end rail portions being especially firm and rigid and of a shape adapted easily and firmly to be grasped by the user.

After the tray has been used, if desired the side and end rail formations may readily be unfolded and flattened out so that the tray may be rolled upon itself for easy disposal in a small space. Alternatively, if desired, the tray may be made of a semi-rigid sheet material of paperboard or other inexpensive fibrous material with surfaces suitably treated to resist moisture and whereby same may be cleaned if desired with a damp cloth or otherwise, permitting the tray to be reused.

In accordance with the invention, the end rail formations which are adapted respectively to be grasped by the two hands of the user in lifting the tray, are preferably formed by folding flap formations, which are integral with the base of the tray, along precreased or weakened fold lines into the shape of tubular formations having a triangular cross-section, for example a cross-section in the shape of a right angle triangle with its right angle at the outer upper corner of the end rail and with its hypotenuse extending from the inner lip of the rail downwardly and outwardly to the base of the rail. Thus the end rails have a cross-section such that the inner upper edges thereof overhang somewhat the base portions of the end rails whereby the user may readily grasp the end rails by placing his fingers on the outer surfaces thereof and with his thumbs in under the inside overhanging portions thereof.

Further in accordance with the invention the side rails of the tray may be formed by flap portions integral with the main part or base of the tray and which are folded upwardly, thence over and downwardly. To secure both the end rail and side rail flap portions in a substantially locked relation to the base or main portion of the tray, the latter may be formed with slots adapted to be removably engaged by complementary lug portions on the edges of the folded-over flap portions. Also at the corners

2

of the tray, to add to the strength and rigidity of the structure, the flaps may be formed with certain extension portions which serve to bring the end and side rail formations into a firm interengaging and substantially locked relation.

Various further and more specific objects, features and advantages of the invention will appear from the description given below, taken in connection with the accompanying drawings, illustrating by way of example a preferred form of the invention.

In the drawings:

FIG. 1 is a perspective view of a preferred form of tray made in accordance with the invention and indicating the manner in which same may be grasped and carried by the user.

FIG. 2 shows the left hand end portions of a blank form of sheet material in flat condition and as properly shaped and provided with fold lines or weakened lines for formation into the desired tray. The right hand portions of this blank, which are not shown are correspondingly shaped.

FIGS. 3, 4 and 5 are sectional views taken substantially along the lines 3—3, 4—4 and 5—5 respectively of FIG. 1.

FIG. 6 is a perspective view of one corner portion of the tray with the various flap portions which form the side and end rails thereof shown in partially assembled relation.

Referring to the drawings in further detail, the bottom or main body portion of the tray is indicated at 10 with side rail formations at 11, 12 and end rail formations at 13 and 14.

As shown in FIG. 2, the blank from which such tray

is to be made is so cut that the portions which are to provide the side rails 11, 12, will be formed of flaps integral with the base 10 and joined thereto along crease lines as at 15. Along the mid-portion of such flaps, a pair of crease lines is formed as at 16, these crease lines being spaced apart by a distance equal to the desired width of the upper edges 17 of the side rails. Along the outer edges of these flaps, they are cut with lug formations as at 18 adapted to cooperate with slots as at 19 cut in the base of the tray along adjacent the fold line 15. Thus each of the flaps which are to form the side rails may be first folded to a position vertical with respect to the base of the tray and then the upper portions of the flap may be folded over inwardly and downwardly about the fold lines 16, while the lugs 18 are inserted into the slots 19, thereby effectively locking the side rail formations in place.

To provide the end rail formations, the base 10 may be formed with integral flaps at each end and each such flap being constituted of three portions as at 20, 21 and 22. The flap portion 20 joins the base along crease line 23 and joins the flap portion 21 along a crease line or perforated weakened line as at 24. Flap portion 21 in turn joins flap portion 22 along another crease or weakened line of perforations 25. The parallel weakened lines 24 and 25 are spaced apart by a distance equal to the width of the flap portion 21, which in turn, as will be apparent, is equal to the desired width of the upper surface of the completed end rail. Flap portion 22 is provided with lug portions as at 26 adapted to be engaged in complementary slit openings as at 27, which preferably are located along the crease line 23, and partially extending into the base portion 10 and partially into the adjacent parts of the flap portion 20. Thus when it is desired to fold the end flaps into formations for providing the end rails, the flap portions 20 are flexed up to vertical positions, then each flap portion 21 may be flexed inwardly to a horizontal position while the flap portion 22 is folded downwardly and out-

wardly so as to bring the lugs 26 into position to extend diagonally downwardly and outwardly through the slits 27, as best shown in FIG. 3.

To provide means for effectively retaining the rail corner portions in their relative desired positions and in a substantially locked relation, the flap portions 20 at each end may be formed with extensions as at 30 which are adapted to be folded over and embraced between the folded portions of the side rail flaps when the tray is in set-up or assembled condition. The manner in which these flap extensions 30 may be folded into place to be engaged by the side rail flap portions is best indicated in FIG. 6. That is, as the end rail flap portions 20, 21 and 22 are brought to the position shown in FIG. 6, the extension portions 30 may be folded in, just prior to the time when the portions of side rail flaps 12 are folded over into positions to embrace the extensions 30. The extensions 30 may be joined to the flap portion 20 along crease lines as at 31 and thus the area of juncture serves to complete and close the rail corner formation while at the same time the flap extension portions 30 may extend far enough into embraced relation by the side rail flap portions so that the end rail flap portions 20 will be securely held in proper position, thereby insuring that the remaining end rail flap portions 21 and 22 will also be held in position by reason of the lug and slot formations 26 and 27, as shown in FIG. 3.

As best indicated in FIGS. 3 and 6, in case the tray is formed of corrugated paperboard or the like, the corrugations may preferably extend in a direction so as to run longitudinally of the end rail flap portions 20, 21 and 22, thereby contributing to the rigidity of the end rails when folded into position.

Although a certain particular embodiment of the invention is herein disclosed for purposes of explanation, further modifications thereof, after study of this specification, will be apparent to those skilled in the art to which the invention pertains. Reference should accordingly be had to the appended claims in determining the scope of the invention.

What is claimed and desired to be secured by Letters Patent is:

1. A paperboard blank adapted to be folded into a rigid tray, said blank comprising a main base portion of substantially rectangular configuration, an end flap handle construction formed along each opposite end edge of said main base portion, said end flap handle construction comprising first, second and third handle flap portions which extend longitudinally of said end edges, each said first handle flap portions being integral with one of said end

edges along a first handle flap fold line, said first handle flap fold line having handle flap lug slots formed therein, each said second handle flap portion being integral with and interconnecting said first and third handle flap portions along second and third handle flap fold lines respectively, said second handle flap portions being of substantially the same width as said first handle flap portions, the outer edge of said third handle flap portion having protruding lugs thereon at locations corresponding to said handle flap lug slots, said handle flap portions being of relative width to form a right triangular cross sectional configuration when said first and second handle flap portions are bent at right angles about said first and second fold lines and said lugs are inserted into said lug slots, the width of such handle flap portions further being such as to form said triangular configuration of a size which may be conveniently grasped by full encirclement with the thumb and fingers of a user's hand, tab flaps extending from the ends of said first handle flaps, first and second side rail flap portions extending longitudinally along each opposite side edge of said main base portion and first side rail flap portions being integral with and connected to said main base portion along a first side rail fold line having lug slots formed therealong, each said second side rail flap portion being integral with and connected along the outer edge of a first side rail flap portion along a second side rail fold line, the outer edge of each said second side rail flap portions having lugs protruding therefrom at locations corresponding to the lug slots formed along said first side rail fold lines, the width of each side rail flap portions being substantially equal to the width of said tab flaps so as to fold about and snugly enclose said tab portions when said end flap portions are folded into said triangular cross sectional configuration.

2. A paperboard blank as defined in claim 1 wherein said blank is of a double face corrugated paperboard material formed with corrugations extending longitudinally of said handle flaps.
